UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

LAMP-SOCKET AND THE LIKE.

1,228,026.

Specification of Letters Patent. Patented May 29, 1917.

Application filed March 24, 1913. Serial No. 756,432.

To all whom it may concern:

Be it known that I, CHARLES J. KLEIN, a citizen of the United States, residing at Milwaukee, in the county of Milwaukee and State of Wisconsin, have invented new and useful Improvements in Lamp-Sockets and the like, of which the following is a full, clear, concise, and exact description, reference being had to the accompanying drawing, forming a part of this specification.

This invention relates to lamp sockets, pendent switches, and the like.

It has among its objects to provide an improved locking means for holding the parts of a casing and the device contained therein against relative rotation and axial separation, and also to provide insulating means for the conducting parts.

Certain further objects will be pointed out hereinafter.

In order that my invention may be fully set forth and clearly understood, I have shown in the accompanying drawing, one embodiment thereof as applied to a lamp socket of the push-button type. It is to be understood, however, that the invention is susceptible to modification and application to other uses without departing from the scope thereof.

In the drawing,

Fig. 1 is a sectional view of the lamp socket;

Fig. 2 is a perspective view of the inner face of one part of the insulating cover;

Fig. 3 is a perspective view of the outer face of the part shown in Fig. 2;

Fig. 4 is a perspective top view of the same;

Fig. 5 is a sectional view of the casing cap;

Fig. 6 is a bottom view of the same;

Fig. 7 is a top view of the casing shell;

Fig. 8 is a side elevation of the same partially broken away; and,

Fig. 9 is a view at right angles to Fig. 8, also partially broken away.

The structure illustrated includes an insulating base 1 adapted to carry on its upper face a switch mechanism (not shown) and carrying on its lower face a screw shell 2. Terminals 3 are also mounted on opposite sides of the base to receive line wires. The terminals 3 are accessible from the sides of the base as shown and the screw shell 2 is secured to the latter by screws 4 located at substantially right angles to the terminals.

The base is contained in a casing comprising a cap 5 and a shell 6. The cap and shell are adapted to telescopically unite and are provided on their attaching ends with interengaging latches, described hereinafter. In order to house the switch mechanism and insulate the line conductors I provide an insulating cover designed to be mounted on the base 1.

This insulating cover is preferably vertically divided into two symmetrical sections 7. It will be obvious, however, that it may be made in one piece, if desired. As shown, each section of the cover is substantially semi-cylindrical and has a semi-circular chamber 8 in its lower end adapted to house the switch mechanism. At the top of each section of the cover is a semi-circular recess 9 with oppositely disposed channels or recesses 10 inclined downwardly from the center toward the sides of the cover. Thus when the parts of the cover are fitted together a central circular opening is provided in its top, and divided tunnels extend downwardly therefrom. These tunnels act as passages for line conductors leading to the terminals 3. The cover has a circumferential flange 11 intermediate its ends, which rests upon the upper edge of the shell 6 and abuts the flanged shoulder 12 of the cap 5 when the parts are assembled to limit further telescopic attachment thereof. Recesses 13 are provided on opposite sides of its lower end to receive the operating member of the switch mechanism. Rectangular projections 14 are also provided below the flange on opposite sides of the cover and preferably at points directly above the recesses 13 therein, as shown in Fig. 3. The sections of the cover are secured to the base by means of the usual screws 4 which secure the base and screw shell together and which in this case are countersunk in the cover. It will thus be seen that line wires may be inserted through the cover and attached to the terminals 3 without removal of the cover, since the tunnels 10 afford an unobstructed passage from the central opening 9 to the terminals. The latter remain accessible from the sides of the base as already described. If desired, however, one section of the insulating cover may be removed by loosening one of the screws 4. The terminals thus become entirely exposed and the line wires may be more readily attached thereto. After the conductors are

connected the removed section of the cover may be easily replaced and the conductors concealed in the divided tunnels.

The casing provided to inclose the socket 5 comprises the receiving cap 5 and the shell 6. The locking means for these parts includes an inturned marginal portion or flange 15 on the lower edge of the cap. This flange is preferably reinforced to prevent bending. As shown this stiffening is accomplished by pressing the inner edge of the flange upwardly, and thus forming a curved bead 15 between the flat ledge and the lower margin of the cap. The cap is also preferably provided with an annular shoulder 12 spaced from its lower edge and located at the union of the straight wall and tapered top of the cap. The flange has two oppositely disposed notches 17 preferably cut to the rim of the cap as shown, and, at 90° therefrom, additional smaller notches 18 cut into the flat ledge.

The shell 6 has oppositely disposed slots 19 in its upper end for increasing its resiliency and accommodating the reciprocating push bar of the switch mechanism. The projections 14 on the insulating cover are also received in the slots 19 so that the socket is held in fixed position within the shell. At the edge of these slots the metal of the shell is bent outwardly to form vertically extending lugs 20 which afford flat stops for the projections 14 on the insulating cover and which also coöperate with the cap to prevent relative rotation of the shell, as will be described. Around the periphery of the shell and preferably at right angles to the slots 19, are a plurality of outwardly pressed nibs 21 having horizontal lower edges. The metal of the shell about the nibs 21 is stiffened to increase its strength by providing ribs 22 therein extending downwardly a slight distance from the top of the shell.

When it is desired to assemble the parts of the device, line conductors are inserted through the opening in the receiving cap and brought directly through the central opening in the insulating cover, through the tunnels therein, to the terminal posts. The insulating cover with the base 1 and screw shell 2 fit snugly into the shell 6. The reciprocating push bar of the switch mechanism and the projections 14 on the cover thereabove drop into slots in the shell while the circumferential flange 11 of the cover rests upon the upper edge of the shell. By now turning the shell so that the lugs 20 register with the notches 17 in the cap, the shell may be pushed into engagement therewith until the flange 11 on the insulating cover abuts the shoulder 12 on the interior of the cap. When the shell and cap are attached the faces of the lugs 20 coact with the sides of the notches 17 to prevent rotary

movement while the edges of the nibs 21 coact with the face of the flange 15 in radial alinement with the notches 18 to prevent axial separation.

At the same time separation of the parts is readily accomplished by pressing the shell inwardly beneath the oppositely disposed lugs, and thus disengaging the latter from the flange of the cap. Compression of the shell is permitted at these points by making the insulating cover of reduced size below the flange.

It will thus be noted that by my improved construction I have provided practical and easily manufactured means for efficiently insulating line conductors from receiving caps without the use of separately lining the caps, and I have also provided an exceedingly simple locking means for the parts of the casing, particularly adapted for efficient use with the other parts of the improved device.

What I claim as new and desire to secure by Letters Patent is:

1. In combination, a casing for lamp sockets comprising a cap and shell, a supporting base therein for the current carrying parts, and an insulating member within said casing and removably secured to said base independently of said cap to insulate conductors to be connected with said current carrying parts from each other and from said cap.

2. In a lamp socket or similar device, in combination, a casing comprising a conductor receiving cap and a shell, a supporting base within said casing adapted to carry a switch mechanism and oppositely disposed terminals accessible from the sides thereof, and an insulating cover secured to said base for interiorly insulating said conductor receiving cap, said cover having a plurality of recesses therein providing free passage for conductors to be connected to said terminals and having a chamber for housing said switch mechanism.

3. In a lamp socket or similar device, in combination, a casing comprising a cap and shell, an insulating base therein carrying oppositely disposed terminals adapted to receive conductors, and a divided insulating cover having its parts independently secured to said base at points spaced from said terminals for insulating said conductors from said cap, the parts of said cover being independently detachable.

4. In a lamp socket or similar device, in combination, a receiving cap provided with an inturned marginal portion, a resilient shell having lugs adapted to coöperate with said marginal portion to lock said cap and shell against relative rotation and axial separation, an insulating base within said shell for the current carrying parts including terminals, and an insulating cover secured

to said base and lining said cap, said cover having a central opening in its top registering with the opening in said receiving cap, tunnels extending therefrom to said terminals for the reception of line wires, and a projection adapted to coöperate with certain of said lugs on said shell to lock said base against rotation within said shell.

5. A resilient shell for lamp sockets having a projecting lug adjacent one end, the

metal of said shell being stiffened about said lug.

In witness whereof, I have hereunto subscribed my name in the presence of two witnesses.

CHARLES J. KLEIN.
